DESIGN FOR A CRUTCH

Charles B. Neptune, Los Angeles, Calif.

Application June 14, 1946, Serial No. 130,725

Term of patent 14 years

(Cl. D83—1)

To all whom it may concern:

Be it known that I, Charles B. Neptune, a citizen of the United States, residing at Los Angeles, in the county of Los Angeles, State of California, have invented a new, original, and ornamental Design for Crutch, of which the following is a specification, reference being had to the accompanying drawings, forming a part thereof, in which:

Fig. 1 is a side elevational view of a crutch embodying my new design;

Fig. 2 is an enlarged sectional view thereof, taken through 2—2 of Fig. 1;

Fig. 3 is an enlarged partial sectional view thereof, taken through 3—3 of Fig. 1;

Fig. 4 is a top plan view of the arm rest of said crutch;

Fig. 5 is a transverse sectional view of the arm rest, taken through 5—5 of Fig. 1; and,

Figs. 6, 7, and 8, are slightly enlarged sectional

views, taken on the lines 6—6, 7—7, and 8—8, respectively, of Fig. 1.

I claim:

The ornamental design for a crutch, substantially as shown.

CHARLES B. NEPTUNE.
